FURNACE

William Raisch, New York, N. Y., assignor to
Underpinning & Foundation Co., Inc., New
York, N. Y., a corporation of New York

Application September 5, 1936, Serial No. 99,627

12 Claims. (Cl. 110—12)

This invention relates to improvements in furnaces of the type in which material is introduced at the top of a furnace and falls on a hearth and is then agitated and rabbled to one or more outlets by suitable rabbling devices.

Usually the material to be treated is introduced intermittently into the furnace but in course of time it is bound to fall on the rabbling device or devices, an occurrence which is undesirable for various reasons. For example, some of the material falling on a rabbling device will be retained thereon and will not be discharged from the hearth or compartment of which the hearth forms the bottom, in the usual course of operation and, even if it finally drops from the rabbling device to the hearth, it will not be in the same condition as the material dropped directly on the hearth and rabbled directly to the outlet or outlets. As a matter of fact the tendency would be for the material to cake and harden on the rabbling devices, thus interfering with their operation and action and necessitating cleaning from time to time.

Although the undesirable feature of having material cake on the rabbling devices would occur in the use of any kinds of material, wet and sticky material, such as sewage sludge and the like, would be particularly troublesome. Obviously in a multiple-hearth furnace with vertically spaced hearths and one or more rabbling devices for each hearth, the principal trouble would be at the uppermost hearth where the material would usually be at its stickiest. In passing over the first hearth the material would be freed to a substantial extent of moisture and volatile matter and therefore would not be so sticky. Furthermore the material is fed more regularly from one hearth to another and does not fall in substantial masses as it does on the uppermost hearth.

The principal object of the invention is to provide advantageous and efficient means to avoid the aforesaid and other difficulties experienced in machines heretofore in use.

Another object is to provide means for preventing material introduced at the top of the furnace from falling on a rabbling device. A further object is to prevent the fall of material on a rabbling device, including one or more members positioned to obstruct the downward passage of such material as the rabbling device passes under the charging opening.

According to a preferred manner of carrying out the invention, the invention is embodied in a furnace in which a rabbling device extends radially from a vertical shaft and over a hearth

on which the material falls from the charging opening in the top of the furnace. The prevention of the fall of freshly charged material on the rabbling device may be effected through a hinged-door device which may include one door only but 5 preferably has two doors. These doors may be counterbalanced and operatively connected so as to open and close simultaneously and through suitable connections may be controlled by a cam mounted on the vertical shaft so that they will 10 be closed during each passage of a rabbling device beneath the same. The supply of material to the cam-controlled door may be controlled by a separate set of pivoted doors normally held in closed position by suitable counterbalancing means. 15 In operation material is charged on the upper set of doors and as soon as sufficient material has fallen on these doors they open and the material drops to the cam-controlled doors and will ordinarily pass through the same unless prevented by 20 the cam means as a rabbling device passes beneath the charging opening. As soon as the rabbling device passes the charging opening, the doors are released from the cam control.

Other objects, features and advantages will appear upon consideration of the following description and of the drawing in which:

Figure 1 is a fragmentary horizontal section of a furnace embodying a preferred form of the present invention; and

Figure 2 is a section taken along the line 2—2 of Figure 1.

Referring to the drawing, there is illustrated a furnace 10 comprising a top 11, a hearth 12 spaced downwardly therefrom, and a peripheral wall 13 supporting said top 11 and said hearth 12. At the axis of the furnace is a vertical hollow shaft 14 extending through the central part of a central discharge opening or outlet 15 and through an opening 16 in the top 11. At the opening 16, there may be provided a gas seal 17 to prevent the passage of gases between the shaft 14 and the edge of the top 11 around the opening 16.

In the compartment between the top 11 and the hearth 12, the shaft 14 may be provided with one or more rabbling devices 18, each of which comprises a radial arm 19 and blades 20 inclined so that, when the shaft 14 is rotated in clockwise direction as viewed in Fig. 1, the material is 45 rabbled toward the central opening 15 to pass downwardly, for example to a lower hearth, not shown. The top 11 may be provided with a charging opening 21 through a chute 22 having at its top a hopper 23, and just beneath the hop- 55

per a door device comprising two doors 24 mounted on shafts 25 and counterbalanced as by arms 26 and weights 27, so as to remain closed except when the weight of material in the hopper 23 is sufficient to open them.

According to the present invention, it is proposed to prevent material introduced into the furnace through chute 22 from falling on the rabbling devices 18. To this end, the chute 22 is made much higher than usual and provided at a suitable distance beneath the doors 24 with an additional door device preferably comprising two doors 28 mounted on shafts 29 and urged to closed positions by suitable means such as arms 30 and counterbalancing weights 31. Preferably the distance between the doors 24 and the doors 28 is sufficient to have greater capacity than the hopper 23, thus enabling the sets of doors to be more nearly independent in their action. The doors 28 may be caused to open and close simultaneously by intermeshing gear members or sectors 32 mounted on the shafts 29.

To hold the doors 28 closed when a rabbling device 18 is passing beneath the charging opening 21, one of the shafts 29 may be provided with an arm 32 so fixed thereon that movement of the outer end thereof away from the axis of the furnace will close the doors and act to hold them closed. Such outward movement may be effected through a push member or link 33 pivoted to said outer end of the arm 32 and to the lower end of a downwardly extending arm 34 fixed on a shaft 35 rotatable in bearings 36 on a stationary frame above the top of the furnace. Fixed on the shaft 35 and extending downwardly therefrom is an arm 37 carrying on its lower end a roll 38 adapted to be engaged and moved away from vertical shaft 14, by suitable cam means, to close the doors 28 and hold them in closed position.

The cam means acting on the roll 38 may be of any desired form but, as illustrated, it comprises an annular cam member 39 encircling the upper part of the hollow shaft 14 and secured thereto. At its circumference or periphery the member 39 is provided with an upwardly projecting flange 40 which limits the outward movement of the roll 38 and consequently the upward movements of the doors 28. Upward movement of the doors 28 to closed position and locking of these doors in closed position may be effected by a cam 41 formed by an upwardly projecting flange and having an operating portion 42 for each rabbling device 19 of which three are indicated on the drawing. Each of these operating portions 42 may be considered as a separate cam and is provided with a gradually curved forward side adapted to move the roll 38 outwardly, an end portion or dwell to hold the roll 38 in its outermost position and a concave rear side arranged to permit free movement of the roll toward the shaft 14 as soon as the dwell portion moves out of contact with the roll. It will be evident that the flange 40 might be omitted and that a stop in some other location may be used. One advantage of utilizing the flange or rim 40 as a stop is that the flange is located close to the dwell portions of the operating cam portions 42 and it is therefore relatively easy to hold the roll 38 against radial movement between one of said dwell portions and the rim 40.

In operation of the furnace, the shaft 14 is rotated by any suitable means and the rabbling devices 18 above the hearth 12 act to agitate the material on the hearth and gradually work it to the central discharge opening or outlet 15 where

it drops to another hearth not shown. Fresh material is supplied to the hopper 23 and when it accumulates to a sufficient extent the weight of the material opens the doors 24 against the action of the counterweights and the material flows into the space above the doors 28 which usually open in turn and permit the material to drop on the hearth 12. If, however, a rabbling device 18 is immediately beneath the charging opening the doors 28 are held closed and if a rabbling device moves under the opening just after the doors 28 have opened these doors will be moved to closed position until the rabbling device has moved past the charging opening.

It should be understood that various changes may be made and that certain features may be used without others, without departing from the true spirit and scope of the invention.

Having thus described my invention, I claim:

1. In an apparatus of the character described, the combination with a hearth, a charging device to drop material on said hearth and a rabbling device traveling between the charging device and the hearth and over all parts of the hearth on which the material is dropped, of means for preventing material supplied by said charging device from being deposited on said rabbling device.

2. In an apparatus of the character described, the combination with a hearth, a charging device to drop material on said hearth and a rabbling device traveling so as to pass between the charging device and the hearth, of means for controlling the charging device to prevent the dropping of material therefrom while the rabbling device is beneath the charging device.

3. In an apparatus of the character described, the combination with a furnace top having a charging opening, a hearth to receive material from said charging opening, means including a counterbalanced door for controlling the passage of material through said charging opening, a radially extending rabbling device above said hearth and traveling so as to pass beneath said charging opening, of means holding said door closed while the rabbling device is passing the charging opening.

4. In a furnace of the character described, the combination with a furnace top having a charging opening, a hearth to receive material from said charging opening, means including a counterbalanced door for controlling the passage of material through said charging opening, a radially extending rabbling device above said hearth and rotating about the axis of the furnace so as to pass beneath said charging opening, of means for closing said door as the rabbling device approaches the charging opening and holding the door closed while it is passing the charging opening.

5. In an apparatus of the character described, the combination with a furnace top having a charging opening, a hearth to receive charged material, means including a counterbalanced pivotally mounted door for controlling the passage of material through said charging opening, a radially extending rabbling device beneath said furnace top and traveling so as to pass beneath said charging opening, of means holding said door closed while the rabbling device is passing the charging opening, the door-holding means including a cam moving with said rabbling device and a lever connected with said door and operable by said cam.

6. In an apparatus of the character described,

the combination with a furnace top having a charging opening, a hearth beneath said opening to receive the material, means including a counterbalanced pivotally mounted door for controlling the passage of material through said charging opening, a plurality of radially extending rabbling devices over said hearth and traveling so as to pass beneath said charging opening, of means holding said door closed while the rabbling device is passing the charging opening, the door-holding means including a plurality of cams traveling with said rabbling devices and a lever connected with said door and engageable by said cams substantially at the times when the corresponding rabbling devices pass beneath said door.

7. In an apparatus comprising a furnace chamber having a top, a chute extending through said top, a counterbalanced door device to control the passage of material through said chute, a hearth spaced downwardly from said top to provide a compartment therebetween, said hearth being provided with discharge means, a vertical shaft, and a rabble device over said hearth and operated by said shaft to travel beneath said chute and move the material on said hearth toward said discharge means, door-controlling means for preventing opening of said counterbalanced door device when the rabbling device is beneath the same, said door-controlling means including a cam rotated by said shaft and a movable member operatively connected with said door device and engaged by said cam to hold the door device closed when the rabble device is passing said chute.

8. In an apparatus of the character described, the combination with a furnace chamber having a top, a chute extending through said top, a weighted-door device to control the passage of material through said chute, a hearth spaced downwardly from said top to provide a compartment therebetween, said hearth being provided with discharge means, a vertical shaft, and a rabble device over said hearth and operated by said shaft to agitate the material on said hearth and gradually discharge it from the hearth, of a second counterweighted door device beneath the first-mentioned door device and means for preventing opening of said second counterweighted door device when the rabbling device is beneath the same.

9. In an apparatus of the character described, the combination with a furnace chamber having a top, a chute extending through said top, a weighted-door device to control the passage of material from said chute, a hearth spaced downwardly from said top to provide a compartment therebetween, a vertical shaft, and a rabble device over said hearth and operated by said shaft to discharge the material from said hearth, of means for preventing opening of said counterweighted door device when the rabbling device is beneath the same.

10. In an apparatus of the character described, the combination with a furnace chamber having

a top, a chute extending through said top, a counterbalanced-door device to control the passage of material from said chute, a hearth spaced downwardly from said top to provide a compartment therebetween, said hearth being provided with discharge means, a vertical shaft, and a rabble device over said hearth and operated by said shaft to move the material on said hearth toward said discharge means, of controlling means for preventing opening of said counterbalanced door device when the rabbling device is beneath the same, said controlling means comprising a cam follower connected with said counterbalanced-door device and a cam on said shaft having an operating part with a forward side adapted to force said cam follower away from the shaft and close the door device and an end in the form of a dwell to hold the door closed for the required period of time.

11. In an apparatus of the character described, the combination with a furnace chamber having a top, a chute extending through said top, a counterbalanced-door device to control the passage of material from said chute, a hearth spaced downwardly from said top to provide a compartment therebetween, said hearth being provided with discharge means, a vertical shaft, and a rabble device over said hearth and operated by said shaft to move the material on said hearth toward said discharge means, of controlling means for preventing opening of said counterbalanced door device when the rabbling device is beneath the same, said controlling means comprising a cam follower connected with said counterbalanced-door device, a cam on said shaft having an operating part with a forward side adapted to force said cam follower away from the shaft and close the door device and an end in the form of a dwell to hold the door closed for the required period of time, and a ring serving to limit the outward movement of the cam follower and serve as a stop for the door device.

12. In an apparatus of the character described, the combination with a furnace top having a charging chute, a hearth to receive material from said chute, chute-closing means including a pivoted door and counterbalancing means to hold the door closed until a sufficient amount of material to overcome the counterbalancing means accumulates on the door, a radial rabbling device rotating about the axis of the furnace and beneath said charging device, of means for preventing material from the chute from falling on the rabbling device including a cam follower connected with the door to control the movement of said door and a rotary device cooperating with said cam follower and having an operating part to move the cam follower in one direction to close the door when the rabbling device passes the chute and a circular part to limit the movement of the follower in the opposite direction and thereby determine the closed position of the door.
